ATTORNEY

UNITED STATES PATENT OFFICE

ROY F. CHAMBERS, OF SAN GABRIEL, CALIFORNIA

CHIMNEY STRUCTURE

Application filed December 5, 1927. Serial No. 237,669.

My invention relates to a chimney structure and to a liner for the throat portion of the chimney.

The objects of my invention are: First, to provide a chimney throat liner which will provide smooth lines and unobstructed surfaces for the passage of the gases of combustion from the firebox to the chimney flue; second, to provide a liner of this class which will facilitate the construction of the throat portion of chimneys and also provide means for supporting the brick of the chimney at the throat portion in position; third, to provide a liner of this class which will deflect the heat from the brick and mortar and keep the extreme heat away from such bricks and mortar at the crown or the usual inclined front wall of the throat of the chimney, thus reducing to a minimum the cracking of brick and mortar and the separation of the two, thereby protecting the same and materially increasing the life of the chimney and of a fireplace; fourth, to provide a liner of this class which will reduce to a minimum the frequent fire hazards occasioned by the fire and hot gases passing through the crevices between the cracks in the brick and the cracks in the separations between the brick and mortar, which permit fire to pass through the bricks to the woodwork usually employed to finish the exterior of the fireplace or the room side of the chimney; fifth, to provide a liner of this class which will not only prevent the fire from passing through the bricks, but will also eliminate the cause causing cracks in or the separation of bricks lining the chimney throat; sixth, to provide a liner of this class which will reduce to a minimum the irregularities on the inside of the chimney throat, thus eliminating the usual smoke pockets often causing smoke to return into the room; seventh, to provide a novelly constructed molded chimney throat liner; eighth, to provide novel means for supporting the throat liner within the chimney throat; ninth, to provide as a whole a novelly constructed chimney; and, tenth, to provide a chimney and liner of this class which are simple and economical of construction, durable, which will not readily deteriorate, one which may be easily and economically

molded, and which may be easily stacked one above the other for storing the same.

With these and other objects in view, as will appear hereinafter, my invention consists of certain novel features of construction, combination and arrangement of parts and portions, as will be hereinafter described in detail and particularly set forth in the appended claims, reference being had to the accompanying drawings and to the characters of reference thereon which forms a part of this application in which:

Figure 1 is a partial front elevational and partial sectional view of my chimney structure incorporating my invention and showing my new throat liner constructed therein; Fig. 2 is a sectional elevation view thereof taken at 2-2 of Fig. 1; and, Fig. 3 is a perspective view of my throat liner separate and apart from the remaining portions of the chimney.

The chimney structure, illustrated in the drawings, and consisting essentially of the fireplace 1 with its firebox 2, ornamental facings 3, and shelf 4, and the chimney flue 5 and the flue liner 6, are for the most part of substantially the same construction as the conventional chimney, or fireplace and chimney flue. The firebox 2 is usually provided with an arched fire brick backing 7 which extends from the base of the firebox in curved form upwardly and forwardly to the chimney throat 8 forming behind the upper portion of this backing a shelf or ledge 9 for directing the return draft passing downwardly at the rear side of the chimney flue. At the lateral sides of the firebox and at the upper ends of the side walls thereof, are provided supporting ledges 10 which are at the same elevation as the upper end of the firebrick facing 7, as shown in Figs. 1 and 2. My chimney throat liner, designated 11, is positioned within the throat portion of the chimney and is supported at the lower edges of its lateral sides on the ledges 10 and at the lower edge of its front side or wall at the upper edge of the structural angle iron or other structural iron member 12 usually employed to support the lower row of brick forming the upper side of the opening of the fireplace, as shown in Fig. 2.

My chimney throat liner, in its preferred form of construction, is made of terra cotta and molded as a single and complete unit in the form shown. This form is a hollow truncated pyramid having a flat and vertical rear wall 11^a, a front wall 11^b which is in the shape of a trapezoid and inclined backwardly and upwardly, and lateral side walls, also trapezoidal in shape, inclined inwardly and upwardly and joining at its edges the lateral edges of the rear and front walls, as indicated by 11^c. The inner faces of the walls forming this liner connect the firebox, at the upper portion thereof, in smooth lines and in unobstructed surfaces, with the inner faces of the flue liner 6 of the chimney flue 5. The portion of the fireplace behind the facing 3 is usually built up of brick and the forward wall of the chimney throat formed as steps in various irregular form forming pockets and materially obstructing the passage of the gases of combustion and smoke to the chimney flue, often causing the same to pass downwardly into the room. By employing my flue liner, the brick and mortar forming the front and lateral sides of the throat portion may be laid against and constructed upon the liner as a form, thus making a solid, rigid and compact structure, as well as facilitating the construction of the chimney throat. The front wall of the liner directs the heat away from the brick and mortar and reduces to a minimum the destructive action on the same and reducing to a minimum the cracking and separation of bricks. Thus, the common cracking and separation of bricks between the wall forming the front side of the chimney throat and the juncture between the brick shelf at the upper side of the fireplace, and the chimney flue is avoided, and the common setting fire to homes by the passage of sparks and hot gases between these cracks and separations to the wooden headers, designated 13, and the studding, designated 14, as well as other wood or inflammable portions around the chimney, or upper portion of the fireplace or mantel, is eliminated. The same is true also of the other walls forming the chimney throat.

Though I have shown and described a particular construction, combination, and arrangement of parts and portions, I do not wish to be limited to this particular construction, combination and arrangement but desire to include in the scope of my invention the construction, combination and arrangement substantially as set forth in the appended claims.

Having thus described my invention, what I claim as new and desire to secure by Letters Patent is:

1. A molded chimney throat liner open at its lower and its upper ends, the rear wall being flat and substantially vertical, the front wall being inclined upwardly and backward-

ly from its lower to its upper end, and its side walls being upwardly converging with respect to each other and joined to the rear and front walls, all forming a free unobstructed upwardly converging and gradually reducing passage from its lower to its upper end, said liner being adapted to be telescoped over and within other liners for stacking and economically storing the same, the inner surfaces of all walls of one liner, when stacked over another liner, engaging the outer walls of the latter.

2. A chimney throat liner having a large rectangular opening at its lower end and a smaller correspondingly shaped opening at its upper end, one wall of said liner being substantially vertical and the other walls being inclined upwardly and inwardly from the lower to the upper ends of the liner, all forming a free unobstructed upwardly converging and gradually reducing passage from its lower to its upper end, the lower and upper supporting edges of the walls being the width of the thickness of the walls, the lower edges supporting the liner in the chimney throat and the upper edges being adapted directly to support a flue liner, said liner being adapted to be telescoped over and within other liners for stacking and economically storing the same, the inner surfaces of all walls of one liner, when stacked over another liner, engaging the outer walls of the latter.

3. In a chimney structure, a large firebox portion, a chimney flue liner positioned and extending above the same, and a chimney throat liner contracted gradually from its lower to its upper end and having plain walls from its lower to its upper end, the termination of the walls at the extreme upper and lower ends being of the same thickness as intermediate portions, forming narrow supporting edges and upwardly converging smooth lines at the inner and outer sides of the walls, the lower end of said flue liner resting upon and being supported by the narrow edges of the upper end of the throat liner.

4. A molded chimney throat liner shaped as a hollow truncated pyramid wholly open at its upper and lower ends, said liner being adapted to be telescoped over and within other liners for stacking and economically storing the same, the inner surfaces of all walls of one liner, when stacked over another liner, engaging the outer walls of the latter.

In testimony whereof, I have hereunto set my hand at Los Angeles, California, this 16th day of November, 1926.

ROY F. CHAMBERS.
